HARRY A. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

NEEDLE-CYLINDER MECHANISM.

1,112,907.

Specification of Letters Patent.

Patented Oct. 6, 1914.

Application filed June 21, 1913. Serial No. 774,961.

To all whom it may concern:

Be it known that I, HARRY A. HOUSEMAN, a citizen of the United States, residing at Philadelphia, county of Philadelphia, and 5 State of Pennsylvania, have invented a new and useful Improvement in Needle-Cylinder Mechanism, of which the following is a full, clear, and exact description, reference being had to the accompanying drawings, 10 which form a part of this specification.

In patents heretofore issued to me, as, for example, in Patent No. 903,190, dated November 10, 1908, I have shown and described a needle cylinder having slots therein for 15 the reception of the needles, combined with pivoted levers having jaws adapted to hold the shanks of the needles, the needles being moved into and out of operative relation with the cam cylinder by swinging the levers on their pivots. While this construction is operative under ordinary conditions, certain difficulties have arisen in placing the needles in proper engagement with their actuating levers. These actuating levers are 20 pivoted directly below their respective needles, and while they are of limited thickness, any needle which is inserted in its slot from above will, when pushed down to the proper level, extend between the jaws of the lever, 25 provided the lever is in precisely its normal position. If, however, the needle levers become slightly loose in their pivot and therefore rock slightly thereon in the direction of their axes, or if they become slightly 30 bent, the needle engaging ends thereof are apt to be slightly displaced in a circumferential direction so that they no longer maintain the necessary precise alinement with the needles. Consequently, when a 35 needle is inserted in the needle cylinder, the lower end thereof may engage one side of the needle lever and, as the needle is forced down, still further displace the needle lever sidewise, with the result that it is not engaged therewith. This results in imperfect 40 knitting. Further, the cause of the trouble is not always obvious to the operator, and serious loss of time occurs until the condition is discovered and remedied. In my invention 45 I obviate this difficulty by providing means whereby the needle levers are held from any circumferential movement while not obstructing their necessary free radial movement on their axis to enable them to

move their respective needles into and out 55 of operative relation with the cam cylinder.

The invention will be understood by reference to the accompanying drawings, which show a preferred embodiment of my invention, and in which—

Figure 1 is a vertical section through the knitting head showing two needle levers engaged with the guide ring and with two needles on opposite sides of the needle cylinder. Fig. 2 is an inverted plan view of the 65 needle-lever holding ring. Fig. 3 is a fragmentary side view, partly broken away.

a is the needle cylinder in which are formed radial slots *b* extending from the inner periphery outward. The needle cylinder is supported on the spider *m* extending up from the bed plate *n*. In the slots *b* are inserted the needles *c* having butts adapted to engage the cams *f'* of the cam cylinder *f*. A curved rod *g*, extending concentric with the knitting head, extends around that portion of the same provided with needle levers. The needle levers *d* are pivoted on the rod *g*. The jaws *e* of the levers *d* hold the shanks of the needles *c*. The 70 needles are moved into and out of engagement with the cam cylinder by swinging the needle levers *d* on the rod *g*. This construction is substantially the same as that set forth in my said Patent No. 903,190. 75

Formed on the upper ends of the needle levers are outwardly projecting shoulders *h* adapted for engagement with a ring *i*. This ring is provided, on its under face, with radial grooves *j* extending from its inner 80 periphery outward toward, but terminating short of, its outer periphery, the depth of the grooves diminishing in an outward direction. The grooves correspond in number and arrangement with the needle levers 85 and are of a width adapted to receive the shoulders *h* and allow the shoulders to play radially therein without permitting them to have any substantial amount of side motion.

To apply the ring, the same is placed over 100 the needle levers in a concentric position relative to the center of the knitting head and in such position that the grooves *j* aline with the needle levers *d* and is then pressed down until all the needle levers engage their respective grooves. No other support than the needle levers themselves need 105 be provided for the ring. The spider *m* is

cut away to permit the ring *i* to be placed in position, the cut away part of the spider enabling the ring to be properly centered. When the ring is so applied, it is impossible for the needle levers to move sidewise, although free radial movement is permitted, as may be seen by reference to the opposite sides of Fig. 1. The right hand part of the figure shows a needle lever moved into position to cause the corresponding needle to engage the cam cylinder, the shoulder of the needle lever extending only into the inner part of the corresponding groove of the ring. At the left hand side of the figure, the needle lever has swung on its pivot into position to withdraw the corresponding needle from engagement with the cam cylinder, the shoulder of the needle having swung toward the outer portion of the groove.

20 In Fig. 3 the ring has been broken away so that no guide is afforded to prevent the needle lever from swinging laterally. A needle *x* is shown as having been inserted in position and as having engaged the side of a needle lever *y*, with the result of forcing the needle lever to one side so that its jaws fail to engage the needle. This defective condition cannot occur with the use of the ring, inasmuch as the ring not only correctly positions the needle lever for engagement with its corresponding needle, but absolutely prevents any lateral displacement of the lever by the needle.

35 While I have designated the device *i* as a ring, it will be understood that it need not necessarily completely encircle the knitting head, as it need be only of sufficient length to engage all the needle levers, which may be provided for only a portion of the needles.

40 Having now fully described my invention, what I claim and desire to protect by Letters Patent is:

1. In a circular knitting machine, in com-

bination, a needle cylinder, independent needles carried thereby, pivoted levers arranged under and adapted to engage the needles and move them into and out of operative position, said levers having outwardly extending shoulders, and a ring the inner part of which is adapted to rest loosely upon said shoulders and which is provided in its under and inner faces with grooves corresponding to the shoulders and into which the shoulders extend and are guided when the ring is in the position specified. 55

2. In a circular knitting machine, in combination, a needle cylinder, independent needles carried thereby, pivoted levers, thin relatively to their length and breadth, arranged under and adapted to engage the needles and move them into and out of operative position, said levers having at their upper needle-engaging ends outwardly extending shoulders, and a ring surrounding the needle levers having grooves, corresponding to the needle levers, adapted to receive and guide said shoulders. 65

3. A needle lever adapted to move the needles of an independent needle circular knitting machine into and out of operative position, the same comprising an L-shaped pivotable member thin relatively to its length and breadth, one arm of which has a pair of jaws adapted for engagement with the needle, and a shoulder projecting from one edge of the jaw-end of the arm in the plane of the extension of the lever whereby the lever may be guided in its pivotal movement.

In testimony of which invention, I have 80 hereunto set my hand, at Philadelphia, on this 20th day of June, 1913.

HARRY A. HOUSEMAN.
